UNITED STATES PATENT OFFICE.

CHARLES D. WRIGHT AND CHARLES A. FISHER, OF PETERSBURG, ILLINOIS.

AUTOMATIC RESISTANCE CUT-OUT FOR TELEPHONES.

SPECIFICATION forming part of Letters Patent No. 288,909, dated November 20, 1883.

Application filed February 2, 1883. (No model.)

To all whom it may concern:

Be it known that we, CHARLES D. WRIGHT and CHARLES A. FISHER, both of Petersburg, in the county of Menard and State of Illinois, have invented a new and Improved Automatic Resistance Cut-Out for Long-Circuit Telephones, of which the following is a full, clear, and exact description.

The object of our invention is to provide a new and improved attachment for telephone-instruments, whereby all the telephones on the line between the two instruments in communication with each other are cut-out automatically, and whereby the circuit is materially shortened and the resistance is decreased correspondingly.

The invention consists in the combination, with a telephone, of a local battery, a clock-work mechanism for closing the circuit of the local battery, and devices for starting the said clock-work mechanism by means of the current of the line-wires and an electro-magnet in the circuit of the local battery, whereby, when the current of the main line passes through the instrument, it starts the clock-work mechanism, which closes the circuit of the local battery, whereby the armature of the electro-magnet in the circuit of the local battery will be attracted, and will thereby form a short circuit for the current of the main line, so that the same will not pass through the telephone or other coils of the instrument, which is thus cut out automatically.

The invention further consists in devices connected with the above-described mechanism for indicating or showing whether the instrument is cut out or not, and showing how long it will remain cut out.

The invention also consists in various parts and details and combinations of the same, as will be fully described and set forth hereinafter.

Reference is to be had to the accompanying drawings, forming a part of this specification, in which similar letters of reference indicate corresponding parts in all the figures.

Figure 1 is a plan view of our improved cut-out for telephones, showing the same open. Fig. 2 is a longitudinal sectional elevation of the same, showing it closed. Fig. 3 is a detail longitudinal sectional elevation of a part

of the box, showing the position of the key in an instrument that is not cut out. Fig. 4 is a longitudinal elevation of the wheel carrying the insulating strips. Fig. 5 is a plan view 55 of the same.

The line-wires A A' are secured to the binding-posts B B' on the box C. The post B is connected by a wire, a, with one end of the wire of the polarized electro-magnet C' in 60 the box, the other end of the wire of which magnet is connected by a wire, a', with the binding-post D', which is connected with one pole of the telephone or receiver E, the other pole of which is connected with the binding-post D, which is connected by means of a wire, a'', with the binding-post B'. The binding-post B is connected by means of a wire, a'', with a hinge, F, which is connected by means of a wire, a'', with the frame G of an 70 electro-magnet G', which is secured on the bottom of the lid C' of the box. The binding-post B' is connected by means of a wire, a'', with a hinge, F', which is connected by means of a wire, a'', with a metal strip, G'', projecting 75 from the under side of the lid C', and having its free or lower end bent rectangularly. The ends of the wire of the electro-magnet G' on the under side of the lid C' are connected by means of the wire a'' and a'' with the hinges F'' 80 and F'', respectively. The hinge F'' is connected by means of a wire, a'', with a contact-disk, H, secured to the inner surface of one side of the box. A contact-spring, J, is secured to the inner surface of the side of the 85 box in such a manner that its free end is pressed against the contact-disk H, which spring J is connected by means of a wire, b, with a binding-post, K, which is connected with one pole of a local battery, L, the other 90 pole of which battery is connected with a binding-post, K'. A press-button or pin, J', passing through the side of the box, has its inner end resting against the spring J. A spring-lever, L', provided with a handle-knob, L'', is 95 pivoted on the outer surface of the box, and if placed on the outer end of the press-button J' presses the same against the spring J. A gong, M, is secured to the inner surface of the box in such a manner that when the spring J 100 is pressed from the contact-disk H a small button at the end of the spring can strike the

gong and sound the same. The hinge F^2 is connected by means of a wire, b' , with the frame N of a clock-work. In the said clock-work a wheel, O , is mounted on one of the shafts O' , which wheel is provided in its periphery with six notches, d , and at each notch with a block, g , of insulating material, which appears on the upper surface of the wheel O . A contact-spring, P , secured on the frame N , and insulated from the same by means of an insulating block or strip, P' , has its free end resting on the wheel O in such a manner that if the wheel O revolves under the free end of the said spring the free end of the spring successively comes in contact with the insulating-blocks g on the wheel O . The said spring is connected by means of a wire, b^2 , with the binding-post K' . A locking-pawl, Q , pivoted to swing in the horizontal plane and adapted to pass into the notches d in the rim of the wheel O , is connected with a curved wire, Q' , to which a spring, R , is attached, which draws the wire Q' and the locking-pawl Q toward the edge of the wheel O , so that when the locking-pawl Q arrives at one of the notches d it will pass into the same and arrest the wheel O . A rod, f , attached to the pendulous armature C^3 of the polarized electro-magnet C' , is provided at its free end with a ball or block, h , against which the free end of the curved wire Q' rests. One of the arbors of the clock-work is provided at its upper end with a hand, S , which revolves over a dial, S' , divided into six equal parts, which dial is so located that when the lid C^2 is closed down on the box the dial will appear in a circular opening, m , in the lid of the box. The wheels in the clock mechanism must be so arranged that the hand S moves from one subdivision of the dial S' to the next during the same time that passes from the time that one insulating-block g on the wheel O leaves the spring P until the next insulating-block g is under the end of the spring. The electro-magnet G' is provided with an armature, G^2 , adapted to swing to and from the ends of the magnet in the vertical plane, to which armature G^2 a rectangular arm, T , is attached, which projects downward from the armature. To the free end of the said arm T a wire, V , is secured, the other end of which is secured to a crank-arm, V' , on a shaft, W , journaled on the under side of the lid C^2 , and to which a small plate, Y , is secured, on which the words "Off," "Cut-out," or some other word having the same meaning is printed or otherwise produced. The plate Y is mounted on the shaft W in such a manner that when the current does not pass through the electro-magnet when the lid C^2 is closed, the said plate will hang down vertically, and will thus draw the armature G^2 from the end of the magnet G' . When the current passes through the magnet G' and the armature is attracted by the same, the movement of the armature throws the plate Y against the under side of the lid C^2 , so that the said plate will appear in the

opening I in the lid of the box, and thus can be seen by persons looking at the box.

The operation is as follows: Usually the end of the spring J rests on the contact-disk H , and only when the two instruments are to be placed in communication the end of the spring J is removed from the contact-disk H by pressing the pin J' inward and holding it in position by means of the spring-lever L' , as shown in Fig. 3. When the instrument is at rest and not being used, the free end of the spring P rests on one of the insulating-blocks g on the wheel O , and the said wheel is locked in position by the pawl Q , which is in one of the notches d of the wheel. The current enters through the line-wire A at the binding-post B and passes through the wire a , around the polarized electro-magnet C' , through the wire a' , the binding-post D' , the telephone E , back to the binding-post D , and through the wire a^2 to the line-wire A' . The current passing through the polarized magnet C' attracts one end of the pendulous armature C^3 , and thereby the arm f is swung in the direction of the arrow m' , Fig. 1, and pressed against the curved wire Q' , connected with the pawl Q , and thereby the pawl Q is drawn out of the notch d , thus releasing the wheel O and permitting the same to be operated by the clock-work mechanism. As soon as the wheel O is operated it begins to turn, and that insulating-block g on which the spring P has rested is moved or drawn from under the free end of the said spring, which thus comes in contact with the metallic surface of the wheel O and establishes an electrical communication between the local battery L and the wheel O , as the said local battery is connected with the spring P by means of the wire b^2 . The current will then be from the local battery L to the binding-post K' , the wire b^2 , the spring P , the wheel O , the frame N of the clock-work mechanism, the wire b' , the hinge F^2 , the wire a' , the electro-magnet G' , the wire a^3 , the hinge F^3 , the wire a^4 , the contact-disk H , the spring J , the wire b , the binding-post K , and back to the local battery. As the current of this local battery passes through the electro-magnet G' , it attracts the armature G^2 of the same and swings it in the direction of the arrow n' , Fig. 2, thereby establishing contact between the arm T of the armature and the metal strip G^3 on the under side of the lid C^2 , which metal strip G^3 is connected by means of the wire a^6 with the hinge F' , which in turn is connected by means of the wire a^5 with the binding-post B' . If the parts are in the above-described position, the current that enters the instrument through the line-wire A at the post B passes from the said post through the wire a^3 to the hinge F , the wire a^4 to the frame G of the electro-magnet G' , through the frame and the armature G^2 , the arm T , the metal strip G^3 , and the wires a^6 and a^5 to the binding-post B' , and out through the line-wire A' , as the resistance in the last-described line is much less.

than in the polarized magnet C', or, in other words, the current passes the instrument without passing through the electro-magnets or through the telephone or receiving instrument 5 E, whereby the resistance is materially diminished and the person at the instrument is not able to hear the words transmitted through the line-wires A A', as the current of the same will not pass the telephone or receiver. Every 10 instrument on the line is cut out in the same manner as described above. As the armature G² is attracted by its magnet, it swings the plate Y against the under side of the cover or lid C² in the direction of the arrow o', and thus 15 shows the word "Off" in the aperture I, and shows the proprietor of the instrument that he is cut out. The wheel O continues to revolve until the pawl Q arrives at the next notch d, and then the spring R draws the end of the 20 pawl into the said notch, (for, as the current has ceased to pass through the magnet C', the armature C² will be released by this time,) and thus cuts out the local battery, and then the instrument will be in communication with 25 the line again. If the parties communicating with each other wish to continue their conversation, the intervening instruments must be cut out again in the manner described above. The hand S rotates the same as the 30 wheel O, and will thus indicate to the proprietor of the instrument that he is cut out, and how long he must wait until the instrument will be in communication again, as the hand S stops every time the wheel O stops and begins 35 to rotate as soon as the wheel O begins to rotate. At that instrument at which the message is to be received the local battery must not be brought into circuit, and to prevent this the button J' is pressed inward, as shown 40 in Fig. 3, and breaks the electrical connection between the spring J and the contact-disk H. The circuit of the local battery cannot be completed, for when the current passes through the wire a" to the disk H it cannot pass from the 45 same to the spring J. As soon as the spring-lever L is removed the spring J will press the pin J' out again, and the electrical contact between the spring J and the disk H will be completed, and the instrument can be cut out 50 like the rest.

Having thus fully described our invention, we claim as new, and desire to secure by Letters Patent—

1. The combination, with a telephone, of a 55 local battery, a clock-work mechanism, shunt-circuiting devices, and an electro-magnet in the circuit of the local battery, the frame of the said magnet being connected with one pole of the line-wires, and of a strip adapted to be 60 brought in contact with an arm on the armature of the said magnet, the said strip being in connection with the other binding-post of the line-wires, substantially as herein shown and described, and for the purpose set forth.

65 2. The combination, with a telephone, of a local battery, a clock-work mechanism pro-

vided with a series of insulating-blocks and connected with one pole of the local battery, a spring resting on the wheel, provided with the insulating-blocks, and connected with the 70 other pole of the local battery, of an electro-magnet for releasing the clock-work mechanism, which electro-magnet is in the circuit of the line-wires, and of an electro-magnet in the circuit of the local battery, the contacts T G³, 75 and the wires a⁴ a⁵, for the purpose of short-circuiting the circuit of the line-wires, substantially as herein shown and described.

3. The combination, with a telephone, of a local battery, a clock-work mechanism connected with one pole of the local battery, which clock-work mechanism is provided with a wheel having a series of insulating-blocks, a spring connected with the other pole of the local battery and resting on the said wheel, 80 provided with the insulating-blocks, a pawl for locking the said wheel, an electro-magnet in the circuit of the main line, and provided with devices for releasing the said pawl from the wheel, and an electro-magnet in the circuit of the local battery and provided with connections adapted to cut the telephone out of the main line, substantially as herein shown and described, and for the purpose set forth.

4. The combination, with a telephone, of a 95 local battery, a clock-work mechanism provided with a wheel, O, having a series of insulating-blocks, g, arranged at suitable intervals, and notches d at the said blocks, the spring P resting on the upper surface of the 100 wheel O and connected with one pole of the local battery, the other pole of which is connected with the clock-work mechanism, the pawl Q, adapted to pass into the notches d, an electro-magnet for withdrawing the pawl Q 105 from the notches d, and an electro-magnet in the circuit of the local battery, substantially as herein shown and described, and for the purpose set forth.

5. The combination, with a telephone, of a 110 local battery, a clock-work mechanism provided with a wheel, O, having insulating-blocks g, a spring, P, an electro-magnet for releasing the wheel O of the clock-work mechanism, an electro-magnet in the circuit of the 115 local battery, of the dial S', divided into the same number of parts as the wheel O, and of the hand S, adapted to revolve above the dial S' with the same speed as the wheel O, substantially as herein shown and described, and 120 for the purpose set forth.

6. The combination, with a telephone, of the local battery L, a clock-work mechanism for closing the circuit of the local battery, the electro-magnet G' in the circuit of the local 125 battery, and connected with one of the binding-posts of the line-wires, the arm T on the armature of the magnet G', and the contact-strip G³, connected with the other binding-post of the line-wires, substantially as herein 130 shown and described, and for the purpose set forth.

7. The combination, with a telephone, of the magnet G', the armature G², the arm T, the wire V, the shaft W, provided with a crank, V', and the plate Y, attached to the shaft W and provided with the word "Off" or "Cut out," substantially as herein shown and described, and for the purpose set forth.

8. The combination, with a telephone, of the local battery L, a clock-work mechanism to for closing the circuit of the same, an electro-

magnet in the circuit of the local battery, a spring, J, the contact-disk H, and the push-button J', substantially as herein shown and described, and for the purpose set forth.
